ELECTRODE HOLDER

James E. Paulson, Long Beach, Calif.

Application July 11, 1945, Serial No. 604,475

3 Claims. (Cl. 219—8)

1

My invention relates to electrode holders for welding electrodes, and is designed as an improvement over the electrode holder forming the subject matter of my U. S. Letters Patent No. 2,342,966, dated February 29, 1944.

The primary object of the instant invention is to provide a simple form of holder for welding electrodes adapted for operation by thumb or finger pressure to clamp or release electrodes, and which obviates rotation of parts in effecting the clamping or releasing operation, whereby installing electrodes in the holder is materially expedited and rendered easier to accomplish than with the holder of my aforesaid patent.

Other and subordinate objects, also comprehended by my invention, together with the precise nature of my improvements, and the manifold advantages thereof, will be readily understood when the succeeding description and claims are read with reference to the drawing accompanying and forming part of this specification.

In said drawing:

Figure 1 is a view in plan, with parts shown in longitudinal section of my improved electrode holder in a preferred embodiment thereof.

Figure 2 is a view in side elevation, with parts shown in longitudinal section.

Figure 3 is a view in transverse section taken on the line 3—3 of Figure 1.

Figure 4 is a view in plan, partly broken away, of the jaw-operating rod.

Figure 5 is a view in side elevation of the same.

Figure 6 is a view in transverse section taken on the line 6—6 of Figure 5.

Reference being had to the drawing by numerals, the electrode holder of my invention, as shown, comprises a metal electrode clamping and welding bar 1 which is substantially rectangular in cross-section and formed in any suitable length with an enlarged, cylindrical, socket-forming, rear end portion 2 adapted to be abutted by a handle 3 of the same diameter as said portion 2 and which is of the type through which a current conducting cable 4 extends to frictionally fit into a socket 5 formed by said portion 2 so that the handle is aligned with said portion 2 and the cable 4 connected to said portion. A suitable sheath 6 of insulation material, preferably rubber, is fitted around said portion 2 and the handle 3 and is preferably, although not necessarily, secured thereto, as by cement, not shown. A series of semi-circular notches 7 of different sizes, for seating different sizes of electrodes therein, are provided in one edge of said

2

bar 1 adjacent to the front end of the same, and a pair of apertured ears 8 extend from said edge of said bar 1 in the rear of the series of notches 7 and adjacent thereto parallel with the sides of said bar. A single ear 9, similar to ears 8, extends from said edge of said bar 1 immediately in front of the portion 2 and is offset from the plane of the bar.

A short bar-like clamping jaw 10, with a rear end coplanar ear 11 thereon fitting between the pair of ears 8, is pivotally mounted on said ears 8 by a pivot pin 10' traversing said pair of ears 8 and the ear 11, said jaw 10 being swingable on said pin 10' in the plane of said bar 1 into and from clamping relation to the notched portion of said bar 1 with an inner edge opposed to said notched edge portion.

A hollow, tubular, jaw-operating rod 12, with a bifurcated front end 13 straddling the ear 11, is pivoted to said ear by a pivot pin 14 extending through said bifurcated end and said ear 11. The jaw-operating rod 12 extends rearwardly to terminate alongside the portion 2 and the pivot pin 14 thereof is offset laterally outwardly from the pin 10' for a purpose presently clear. As will be understood, the jaw-operating rod 12 lies in a common plane with the jaw 10 and the electrode-clamping and welding bar 1. A longitudinal slot 15 is provided in said operating rod 12 and which extends from the bifurcated end 13 along said rod for a suitable distance in the common plane of said jaw 10 and bar 1. As will be understood, the operating rod 12 is designed to be moved endwise in opposite directions to swing the jaw 10 into and from clamping relation to the notched portion of the electrode-clamping and welding bar 1 to clamp and release electrodes, as at 16, which are thus seated in a selected notch 7 of appropriate size and in complementary notches 7' provided in the opposed edge of the jaw 10.

For moving the jaw-operating rod 12 endwise, the following means is provided: An adjustable rod 17, relatively shorter than said rod 12, is slidably mounted therein with a lateral front end ear 18 projecting out of the slot 15 and connected by a link 19 to the beforementioned ear 9 by a pivot pin 20 extending through the front end of the link, and said ear 18 and a pivot pin 21 extending through the rear end of said link and said ear 9. The ear 9 is laterally offset from said bar 1 so that the link 19 will be disposed parallel with the jaw-operating rod 12. An adjusting screw rod 22 extends into the rear end of the jaw-operating rod 12 and is threaded into

the rear end of said rod 17, said adjusting screw rod being provided with a rear end knurled head 23 adapted to abut the rear end of said rod 12. A thumb, or finger, piece 24 is provided on the rear end of the jaw-operating rod 12 to extend in upright position therefrom alongside the portion 2. The electrode-clamping and welding bar 1 is covered by a sheath 25 of insulation material extending beyond the inner edge of said bar 1 over and below the described operating means, as shown in Figure 3, to prevent contact with the same and the ear 11. The jaw 10 is likewise covered, with the exception of the notched edge portion thereof and the ear 11, with a sheath 26 of similar insulation material. The sheaths 25, 26 may be secured to said bar 1 and jaw 10 in any desired manner.

As will be seen by an inspection of Figure 1, when the jaw 10 is in the described clamping relation, the jaw-operating rod 12 extends substantially parallel to the electrode-clamping and welding bar 1 with its rear end close to the sheathing 3 around the portions 2, and in this position of said rod 12, the pivotal connection 20 of the link 19 to the rod 17 is offset to one side of and past a dead center position relative to the pivot pins 14 and 21 so that said rod 12 is locked in a position to maintain the jaw 10 in clamping relation. This follows, since, in the clamping relation of the jaw 10, said rod 12 is thrust against the head 23 of the adjusting screw rod 22 and said rod 17 thereby exerts a thrust against the link 19. To move the jaw 10 out of clamping relation and release the electrode 16, it is merely necessary to swing the jaw-operating rod 12 on the pivot pin 14 laterally outwardly until the pivotal connection 20 of the link 19 swings outwardly past dead center relation with respect to the pivot pins 14 and 21. In this operation, the throw of the link 19 moves said rod 17 rearwardly in the jaw-operating rod 12, thereby spacing the head 23 rearwardly of the rear end of said rod 12 so that the rod 12 may move endwise rearwardly and permit the jaw 10 to swing out of clamping relation. By turning the adjusting screw rod 22 into or out of the rod 17, the jaw-operating rod 12 may be adjusted endwise relative to said rod 17 to vary the clamping relation of the jaw 10 relative to the notched portion of said bar 1, as may be required in clamping electrodes 16 of different sizes in the notches 7 and 16.

The finger piece 24, as will be obvious, provides for swinging the jaw-operating rod 12 in opposite directions, to cause the described jaw-operating means to assume either locking or releasing position and may be conveniently operated by a finger or thumb of a hand grasping the handle 3 of the holder.

The foregoing will, it is believed, suffice to impart a clear understanding of my invention without further explanation.

Manifestly, the invention, as described, is susceptible of modification both as regards structure and combinations of parts, without departing from the inventive concept, and right is herein reserved to such modifications as fall within the scope of the appended claims.

What I claim is:

1. An electrode holder comprising a handle, an electrode-clamping and welding bar extending forwardly from said handle and having a front end notched portion, a short bar-like jaw pivotally connected to said bar for swinging into and from clamping relation to said portion and

having a notched portion complementing the notched portion of said bar to seat electrodes in the notches of the same, and means to swing said jaw comprising a rod pivoted at one end to said jaw for lateral swinging movement on said pivot and endwise movable to swing said jaw, and means to cause said rod to move endwise as an incident to lateral swinging thereof comprising a link pivotally connected at opposite ends thereof to said bar and rod, respectively, for overthrow movement of the pivotal connection thereof to the rod past dead center relation to the pivotal connection of the link to the bar and the pivotal connection of the link to said rod to said jaw.

2. An electrode holder comprising a handle, an electrode-clamping and welding bar extending forwardly from said handle and having a front end notched portion, a short bar-like jaw pivotally connected to said bar for swinging into and from clamping relation to said portion and having a notched portion complementing the notched portion of said bar to seat electrodes in the notches of the same, and means to swing said jaw comprising a rod pivoted at one end to said jaw for lateral swinging movement on said pivot and endwise movable to swing said jaw, and means to cause said rod to move endwise as an incident to lateral swinging thereof comprising a link pivotally connected at opposite ends thereof to said bar and rod, respectively, for overthrow movement of the pivotal connection thereof to the rod past dead center relation to the pivotal connection of the link to the bar and the pivotal connection of the link to said rod being variable to vary the clamping relation of said jaw with respect to the notched portion of said bar.

3. An electrode holder comprising a handle, an electrode-clamping and welding bar extending forwardly from said handle and having a front end notched portion, a short bar-like jaw pivotally connected to said bar for swinging into and from clamping relation to said portion and having a notched portion complementing the notched portion of said bar to seat electrodes in the notches of the same, means to swing said jaw comprising a rod pivoted at one end to said jaw for lateral swinging movement on said pivot and endwise movable to swing said jaw, and means to cause said rod to move endwise as an incident to lateral swinging thereof comprising a link pivotally connected at opposite ends thereof to said bar and rod, respectively, for overthrow movement of the pivotal connection thereof to the rod past dead center relation to the pivotal connection of the link to the bar and the pivotal connection of the rod to said jaw, and a finger piece on said rod alongside said handle for use in swinging said rod laterally.

JAMES E. PAULSON.
